UNITED STATES PATENT OFFICE

CHARLES L'ENFANT, OF NEW YORK, N. Y.

SAVINGS BANK

Application filed May 9, 1929. Serial No. 361,639.

This invention relates to savings banks, and more particularly to pocket coin savings banks of the character which are commonly used by banking institutions in thrift campaigns and distributed to depositors whereby coins of small denomination may be saved and periodically deposited to the credit of the holder's account.

It is one of the important objects of my invention to provide such a coin savings bank, the outer surfaces of which present a minimum of protuberant or projecting parts so that the bank may be easily inserted into or withdrawn from a case or holder of leather or similar flexible material.

It is also another object of my invention to provide a simplified and improved construction of the outer body or case of the bank, such construction in addition to materially reducing manufacturing cost, also providing means whereby the opposite side walls of the case are rigidly joined or connected so that it becomes impossible to spread or expand these side walls in the endeavor to remove the coins from the bank.

It is an additional object of the invention to provide a coin savings bank of the type wherein a sliding tray is contained within the outer housing or casing, and in conjunction therewith provides a plurality of coin receiving compartments, an important novel feature of my improvements residing in the construction of this tray whereby the coins are clampingly held in the compartments of the bank and metallic rattling prevented, and in the provision of said tray with a novel form of coin guard which permits of the insertion of the coins in the bank compartments, but effectually prevents their removal therefrom while the tray is in position.

It is another object of my present improvements to provide a construction in which the tray is wholly enclosed within the outer casing of the bank, and said tray carrying locking means at one of its ends to cooperate with means on the side edges of the casing and lock the tray within the casing, and also to limit the withdrawal of the tray through the open end of the casing. The tray is provided with means which acts to strip the coins

from the compartments of the bank as the tray is withdrawn. By thus preventing the entire extraction of the tray from the bank casing, loss of time in re-inserting said tray is obviated while permitting of the easy and quick removal of the coins.

With the above and other objects in view, the invention consists in the improved savings bank, and in the form, construction and relative arrangement of the several parts as will be hereinafter more fully described, illustrated in the accompanying drawings, and subsequently incorporated in the subjoined claims.

In the drawings, I have illustrated several simple and practical embodiments of my invention, and in which similar reference characters designate corresponding parts throughout the several views,—

Figure 1 is a horizontal sectional view showing a coin savings bank embodying one form of my present invention;

Fig. 2 is an end elevation thereof;

Fig. 3 is a longitudinal sectional view taken on the line 3—3 of Fig. 1;

Fig. 4 is a transverse section taken on the line 4—4 of Fig. 1;

Fig. 5 is a detail perspective view of the coin removing tray;

Fig. 6 is a similar view of one of the locking members for the tray;

Fig. 7 is a detail elevation showing the means for unlocking the tray from the bank casing;

Fig. 8 is a plan view of the cut or stamped blank of one of the casing sections of the bank;

Fig. 9 is a detail perspective view showing the two casing sections before final assembly;

Fig. 10 is a plan view of the cut or stamped metal blank from which the tray is formed.

Fig. 11 is an enlarged fragmentary longitudinal section of the tray taken on the line 11—11 of Fig. 5;

Fig. 12 is a transverse sectional view similar to Fig. 4 illustrating a slightly modified form of the bank casing, and

Figs. 13 and 14 are plan views of the

stamped sheet metal blanks from which the casing parts are formed.

Referring in detail to the drawings, and more particularly to Figs. 1 to 11 thereof, the body or outer casing of the bank preferably consists of two complementary sheet metal sections. As shown in Fig. 8, each of these casing sections is stamped or cut from sheet metal of the required gauge or thickness to provide a relatively wide part 5 for one side wall of the casing, and a comparatively narrow part 6 for the opposite side wall of the casing. The part 5 has spaced longitudinally extending slots 7 cut therein, and the part 6 is provided with a single similar slot.

At one end of the metal sheet, the same is cut to provide parts integral with the parts 5 and 6 which are adapted to be bent along the line indicated at A to form flanges 8 and 9 respectively, which will extend at right angles to the plane of the side wall sections 5 and 6. Each of these flanges 8 and 9 is provided with a narrow longitudinally extending slot 10.

At its opposite end the metal sheet is provided with a longitudinally extending slot indicated at 11 adjacent each of its opposite side edges.

The sheet metal blank is also folded or bent along the parallel longitudinally extending lines indicated at B to provide the narrow edge wall 12 between the parts 5 and 6 and connecting the same, a longitudinal flange 13 along the opposite edge of the part 6 and contacting with the opposed face of the part 5, and a flange 14 extending longitudinally along the free edge of the part 5. When the metal blank is thus folded, the flange 13 thereof is positioned centrally between the slots 7 in the part 5 of the flank and the flange 9 at the end of the part 6, is engaged with the inner face of the flange 8 on the part 5 while the two slots 10 in these flanges are in registering relation with each other. Thus, the opposed parts 5 and 6 of the casing section will form one longitudinally extending compartment closed on both sides excepting for the slots 7, and one side of a second similar compartment formed by the laterally projecting portion of the part 5 of the casing section.

Having formed two of the sheet metal casing sections in the manner above explained, as shown in Fig. 9 of the drawings, the laterally projecting part 5 of one casing section is arranged over the open side of the other casing section in opposed relation to the wall section 5 of the latter, the flanges 13 and 14 of said casing sections being engaged with each other and the slots 11 in the ends of said flanges being in registering relation. When the two casing sections are thus fitted together, the end flange 8 on the side wall portion 5 of one casing section engages between one end of the end flange 8 of the other casing section and the end of the flange 14 thereof so

that for the width of one compartment of the casing, the flanges 8 of the two sections are in overlapping relation to each other. I now solder or weld the contacting flanges 13 and 14 of the two casing sections to each other, and also preferably apply a coating of solder along the edges of the overlapping end flanges 8. Thus it will be seen that an outer casing is produced in which the opposite side walls at the edges of the case are integrally connected with each other, and said side walls being also rigidly connected by the end flanges 8 and 9 and the longitudinal flanges 13 and 14. The latter flanges provide the casing with three longitudinally extending compartments which are substantially completely closed at one of their ends by the end flanges 8, excepting for the relatively short and narrow slots 10, while each of said casing compartments at its opposite end is entirely open. In stamping out the sheet metal blanks, each of the parts 12 forming the side edges of the casing and adjacent the opposite ends thereof is provided with an outwardly pressed portion forming the shallow internal shoulders 15 and 16 respectively. The shoulders 15 face towards the closed end of the bank casing while the shoulders 16 face inwardly away from the open end of the casing and are connected with the edge walls of the casing by the inwardly sloping or inclined portions 16'.

It will also be noted from the above description that this outer housing or casing of the bank, with the exception of the slight protuberances at its side edges required to provide the shoulders 15 and 16 has the outer surfaces of its walls entirely smooth and uninterrupted by reinforcing beads, and caps or closures or other parts.

The casing above described is adapted to slidably receive a tray which divides each of the three compartments of the casing into a pair of coin receiving channels or raceways. This tray is also of very novel construction and as shown in Fig. 10 of the drawings is produced from a single blank of resilient sheet metal. The metal sheet or blank 17 is of a length substantially twice the length of the bank body or casing, and is stamped or cut to provide therein the spaced parallel longitudinally extending slots 18. One end of the blank has spaced oppositely directed spurs or teeth 19 cut therein, each set of spurs extending across the entire width of the blank, and one set of said spurs being formed in the extreme end edge of the blank.

From the opposite ends of the blank to points in spaced relation to the center thereof, the side edges of the blank are formed with flanges indicated at 20 which are bent to extend at right angles to the plane of the metal sheet for a purpose which will presently appear.

The central portion of the sheet metal blank 17 is bent across its width as indicated by the dotted lines in Fig. 10 of the drawings, to form a hollow tubular portion 21 in each section of the blank which results from the provision of the slots 18 therein.

Thus, it will be understood that this metal sheet is bent or folded on itself to provide the opposed integrally connected metal strips 22 separated by the slots 18. The opposed parts of the metal sheet are longitudinally curved as shown in Fig. 3 of the drawings, by any suitable mechanical means. Normally, these metal strips are slightly bowed outwardly away from each other and due to the inherent resiliency of the metal, will readily yield under pressure. The integrally connected ends of these metal strips which are provided with the two sets of spurs 19 is bent across the width thereof along the line indicated at C intermediate of the two sets of spurs so that the spurs 19 along the end edge of the sheet are disposed in overlapping relation upon the other integrally connected ends of the metal strip 22 as clearly illustrated in Fig. 11 of the drawings. The spurs or teeth 19, which constitute coin guards are preferably bent to approximately the form shown in Fig. 11, the integrally connected body portions of the spurs defining substantially a semi-circle in cross section, and the points of the spurs being reversely or outwardly curved away from the metal strips 22.

It will thus be seen that the tray consists essentially of three sections to be received in the three compartments of the bank case or housing and each tray section having opposed resiliently yieldable portions held in assembled relation by the integrally formed coin guard means on one end of the tray. At the other end of the tray, the tubular part 21 of the intermediate section may be permanently closed if desired by welding or otherwise permanently securing plates over the opposite ends thereof. The inner end of the tubular end part of each of the outer sections of the tray is also similarly closed as shown at 23, while the outer ends of these tubular portions are open. In the tubular part 21 of each of the outermost tray sections, a slidable locking member 24 is mounted and is urged outwardly therefrom by the coil spring 25 interposed between one end of said member and the closed end of the tubular part 21. This end 24' of the locking member is opposed to the narrow slot 10 in the closed end of the casing. The other or outer end of the member 24 preferably has a beveled end edge shown at 26, the beveled surface thereon facing towards the end of the tray section.

From the above description, it will be apparent that when the tubular end portions 21 are inserted in the open ends of the respective compartments of the bank casing,

the connected intermediate flanges 13 and 14 of the casing walls will be received in the slots 18 between the tray sections. As the tray is moved inwardly, the locking members 24 will ride against the edge walls of the casing until the tray is entirely disposed within the casing and between the opposite side walls thereof, at which time the slots 27 in the end edges of the tubular parts 21 of the outer tray sections register with the slots 10 in the closed end of the casing and the locking members 24 are projected laterally by the springs 25 to engage the outer ends of said members under the shoulders 15. The tray is thus locked in the case against removal without the use of the proper key. In the final part of the inward movement of the tray, the portions of the sheet metal blanks 17 which integrally connect the several sections on parts 22 of the tray with each other at the ends of the slots 18 are received in the slots 11 which are provided in the flanges 13 and 14 of the casing sections.

Thus, as will be seen from reference to Figs. 1 and 2, the end of the tray having the guard teeth or spurs 19 thereon is entirely received within the ends of the casing compartments. In the insertion of the tray, the flanges 21 along the outer side edges of the outermost sections of the tray ride against the inner faces of the side walls of the casing. Since the parts 22 of each tray section in the individual compartments of the casing are separated or bowed in opposite directions, when the bank is empty, each coin receiving passage or raceway between the tray parts and the opposed side wall of the casing has a depth for the greater portion of its length which is appreciably less than the thickness of the coin to be received therein. Also, it will be understood that normally the distance between the outer surfaces of the semi-circular part of the coin guard and the opposite side walls of the bank is less than the coin thickness. Therefore, in order to insert a coin, considerable pressure must be applied to force the same into the open end of one of the coin passages between one side wall of the bank casing and the curved part of the coin guard. This coin guard would thereby be depressed and the spurs or teeth sprung inwardly towards the body plate of the tray. After passing beyond the coin guard, the coin which will be visible through the slots 7 in one side wall of the bank may be moved inwardly towards the closed end of the bank casing. The resilient sheet metal strip 22 of the tray section is thus depressed, and will exert a constant yielding pressure against the coin, holding the same tightly against the inner face of the casing wall. Therefore, when only a few coins have been inserted into the bank, they will be properly held against shifting movement therein, avoiding rattling metallic noise by contact of the coins against

the metal parts of the bank. After all of the passages or raceways of the bank have been filled with coins of the proper denomination, the bank is then opened by the use of a proper key. It will of course, be evident that after a coin has once been inserted in the bank, the guard teeth or spurs 19 will effectually prevent any possibility of the coin being removed through the open end of the 10 casing. These guard spurs are so distributed and spaced from the ends of the slots 7, that they cannot be manipulated by the insertion of wires or other implements in order to permit the coin to pass.

15 In order to open the bank and remove the coins, a key similar to that shown in Fig. 7 may be employed having the two pivotally connected members 28 with reduced projections 29 at one of their ends which may be spread apart for the required distance and inserted through the slots 10 in the closed end of the bank casing and the coinciding slots 27 in the tubular parts 21 of the tray and engaged with the inner ends 24' of the 20 locking members. By then pressing inwardly on the two members 28 of the key, the locking members 24 may be drawn inwardly against the action of springs 25 and disengaged from the shoulders 15. By then pushing inwardly on the key, the locking members may be moved beyond the shoulders 15 and the tray at its other end, projected beyond the open end of the bank casing. The projecting part of the tray is now grasped and the 25 tray pulled outwardly. The tubular parts 21 of the tray sections provide shoulders 30 at the inner edge of each of said parts so that as the tray is pulled outwardly from the casing compartments, the coins will also be 30 drawn outwardly with the tray.

When the last coin in each of the several raceways or channels has been exposed beyond the open end of the bank casing, the outer ends of the locking members 24 come 35 into engagement with the shoulders 16 which prevents further outward movement of the tray, thus obviating its complete disconnection from the casing of the bank. The parts therefore, at all times remain assembled and 40 after the coins have thus been stripped and removed from the compartments of the bank, the tray may then be again easily forced inwardly until the members 24' engage the locking shoulders 15 and is then returned to the depositor. It will therefore, be apparent that a bank of this construction 45 enables the teller or other bank official to remove the coins from the bank with a minimum loss of time such as has heretofore been occasioned by the necessity of re-assembling the closely fitting parts of the bank after each removal of the coins therefrom.

In Figs. 12, 13 and 14, I have shown a somewhat modified form of the body or casing of the coin bank, in which the same is

composed of the two sections 31 and 32 respectively. The sheet metal blank of the section 31 as shown in Fig. 13 is cut to provide in its intermediate portion 32 which forms one entire side wall of the bank casing, two parallel series of slits 33, each end edge of the blank having tongues 34 located in line with the respective slits 33 in each series. This blank at one of its side edges has the projecting flanges or extensions 35 and 36. The blank is adapted to be folded along the parallel lines D in spaced relation to each of its ends so as to provide the opposite edge walls 37 and a side wall section 38 which, after folding is disposed in spaced parallel relation to the side wall section 31. The tongues 34 at each end of the folded blank are inserted through the respective series of slits 33 and clinched upon the outer surface of the part 31 of the blank. It will be understood that the flanges 35 and 36 have first been bent at right angles to the plane of the metal sheet, and after folding, the flanges 35 are disposed upon the inner side of the opposite end portions of flange 36. The other section 32 of the bank casing is stamped from a relatively narrow metal sheet to form the side wall 39 of the intermediate compartment of the bank casing, said sheet metal blank being bent along the lines indicated at E to provide the opposite side flanges of this intermediate compartment which correspond to the inner flanges of the other compartments formed from the blank 31. These flanges at their free edges are also provided with spaced tongues 40 to project through the same slots 33 of the part 31 which receive the tongues 34. The ends of the tongues 40 are laterally bent upon the outer surface of the part 31 in an opposite direction from the tongues 34. In this manner, the part 32 forming the intermediate compartment of the bank casing is rigidly fixed in position with respect to the part 31. While I have referred to the provision of the tongues 34 and 40 for securing the elements in properly assembled relation, it is to be understood that other means might be substituted therefor, and the parts permanently fixed against relative movement either by soldering, or mechanical fastening means whereby any projections or protuberances on the outer face of the bank casing may be eliminated. The tray which divides each compartment of the casing into separate coin receiving channels or passages may be of the same construction as that previously described.

From the foregoing description considered in connection with the accompanying drawings, it will be seen that I have materially simplified the construction of coin banks of this character, particularly with respect to the outer casing which is fabricated from two sheet metal parts which may be easily and

quickly assembled to produce a rigid and substantial casing structure and in which externally projecting flanges or other protuberant elements on the opposite side faces of the casing are entirely eliminated so that the bank can be easily and quickly inserted into a leather case or holder or removed therefrom. The invention is further characterized and distinguished from prior devices of this kind, 5 in that the movable tray is provided with coin guard means at one end located within the open end of the bank casing through which the coins are inserted, and said tray being wholly enclosed and concealed within 10 the casing. The construction of this tray in the form of a single stamping of resilient sheet metal insertable within the non-communicating compartments of the outer casing and having the coin guard means also cooperating with the side walls of the bank casing 15 to prevent shifting or rattling of the coins therein is likewise an important factor in reducing manufacturing costs and at the same time, providing an article of this kind possessing maximum durability.

The locking means provided on the opposite end of the tray from the coin guard means, may be of various other forms than that illustrated in the drawings. It is however, a 20 desirable feature that this locking means shall be so constructed, that it will cooperate with the keeper means on the outer casing, not only to retain the tray in its normal fully inserted position within the bank casing but 25 also to limit its withdrawal or outward movement therefrom, thus saving time in the reassemblage of the parts and also obviating possible damage to the tray sections or to the locking means carried thereby.

40 With respect to the slots 7 in the opposite side walls of the bank casing, this is a well-known feature of the prior art devices, and it will be understood that if greater rigidity or strength is desired, these slots may be entirely omitted or spaced openings substituted therefor through which the coins will be visible. Therefore, it is to be understood that 45 while I have herein disclosed several simple and practical embodiments of the essential features of my invention, in the further development thereof, various structural changes may be found desirable, and I accordingly reserve the privilege of resorting to all such legitimate modifications in the form and relative arrangement of the several elements as 50 may be fairly considered within the spirit and scope of the appended claims.

I claim:

1. A coin bank comprising an elongated 60 casing substantially closed at one end and entirely open at its opposite end, and a tray longitudinally slidable in said casing and wholly contained therein when in operative 65 position to form in conjunction with the side walls of the casing a pair of raceways re-

ceiving coins inserted into the open end of the casing, guard means carried by the tray at the latter end of the casing to prevent the extraction of the coins therethrough, and releasable locking means carried by the tray 70 and cooperating with means on the casing wall to lock the tray against sliding movement in the casing.

2. A coin bank comprising an elongated casing substantially closed at one end and entirely open at its opposite end, and a tray longitudinally slidable in said casing and wholly contained therein when in operative 75 position to form in conjunction with the side walls of the casing a pair of raceways receiving coins inserted into the open end of the casing, guard means carried by the tray at the latter end of the casing to prevent the extraction of the coins therethrough, releasable locking means carried by the tray and 80 cooperating with means on the casing wall to lock the tray against sliding movement in the casing, and said tray including longitudinally extending resiliently yieldable parts normally exerting an outward pressure 85 against the opposite side walls of the casing.

3. A coin bank comprising an elongated casing substantially closed at one end and entirely open at its opposite end, and a tray 90 longitudinally slidable in said casing and wholly contained therein when in operative position to form in conjunction with the side walls of the casing a pair of raceways receiving coins inserted into the open end 95 of the casing, guard means carried by the tray at the latter end of the casing to prevent the extraction of the coins therethrough, releasable locking means carried by the tray and 100 cooperating with means on the casing wall to lock the tray against sliding movement in the casing, and one wall of the casing being also provided with keeper means adjacent to the open end thereof engageable by the locking means on the tray to 105 limit the withdrawal of the tray from the casing.

4. A coin bank comprising an elongated casing substantially closed at one of its ends and entirely open at its other end for the insertion and removal of coins therethrough, a member slidably mounted within the casing and in conjunction with the opposite side walls thereof forming separate coin receiving raceways, said member in its operative position being entirely contained within the casing, and coin guard means integrally formed with one end of said member and located within the open end of the casing permitting of the insertion of the coins 115 but preventing their extraction from the raceways in the operative position of said member.

5. A coin bank comprising an elongated casing substantially closed at one of its ends 120

and entirely open at its other end for the insertion and removal of coins therethrough, a member slidably mounted within the casing and in conjunction with the opposite side walls thereof forming separate coin receiving raceways, said member in its operative position being entirely contained within the casing, coin guard means integrally formed with one end of said member and located 10 within the open end of the casing permitting of the insertion of the coins but preventing their extraction from the raceways in the operative position of said member, and means carried by said member at its opposite end 15 for releasably locking said member within the casing.

6. A coin bank comprising an elongated casing substantially closed at one of its ends and entirely open at its opposite end and 20 having spaced longitudinal partitions between its opposite side walls dividing the interior of the casing into non-communicating compartments, a tray having sections slidable in the respective compartments of the casing 25 and cooperating with the side walls of each compartment to provide a pair of coin receiving raceways, said sections being integrally connected at one end of the tray, the latter end of the tray having guard means located within the open ends of the casing 30 compartments permitting of the insertion of the coins into the raceways but preventing their removal therefrom in the operative position of said tray, and means for releasably 35 locking the tray against sliding movement in the casing.

7. A coin bank comprising an elongated casing substantially closed at one of its ends and entirely open at its opposite end and 40 having spaced longitudinal partitions between its opposite side walls dividing the interior of the casing into non-communicating compartments, a tray having sections slidable in the respective compartments of the casing 45 and cooperating with the side walls of each compartment to provide a pair of coin receiving raceways, said sections being integrally connected at one end of the tray, the latter end of the tray having guard means 50 located within the open ends of the casing compartments permitting of the insertion of the coins into the raceways but preventing their removal therefrom in the operative position of said tray, each of the tray sections 55 at its other end having means for stripping the coins from the raceways in the outward sliding movement of the tray through the open end of the casing, and means for releasably locking the tray against sliding 60 movement in the casing.

8. A coin bank comprising an elongated casing substantially closed at one of its ends and entirely open at its opposite end and 65 having spaced longitudinal partitions between its opposite side walls dividing the in-

terior of the casing into non-communicating compartments, a tray slidable in said casing and having spaced slots accommodating said partitions of the casing, said tray adapted to be wholly received within said casing 70 and having means at one of its ends positioned within the open ends of the casing compartments permitting of the insertion of coins into said compartments but preventing their extraction therefrom, and means for 75 releasably locking the tray at its other end to the casing to prevent sliding movement of the tray and the unauthorized removal of the coins.

9. A coin bank comprising an elongated 80 casing substantially closed at one of its ends and entirely open at its opposite end for the insertion of coins, a tray slidable in said casing and consisting of a resilient metal sheet folded upon itself to provide yieldable parts 85 cooperating with opposite side walls of the casing to form two coin receiving raceways therein, locking means movable between the folded parts of the metal sheet at one end of the tray to coact with the casing and releasably lock the tray against sliding movement, and means carried by the tray at its opposite end and positioned within the open end of the casing to permit of the insertion of the coins while preventing their extraction from 90 the coin raceways.

10. A coin bank comprising an elongated casing substantially closed at one of its ends and entirely open at its opposite end for the insertion of the coins, a tray consisting of a resilient metal sheet folded upon itself to provide parts forming in conjunction with the opposite side walls of the casing coin receiving raceways and yieldingly holding the inserted coins against movement therein, said metal sheet at one of its ends having integrally formed coin guards positioned within the open end of the casing in the operative position of the tray and permitting of the insertion of coins into the raceways while preventing their extraction therefrom, and means for releasably locking said tray at its other end to the casing to prevent sliding movement of the tray and the unauthorized removal of the coins. 100

11. A coin bank comprising an elongated casing substantially closed at one of its ends and entirely open at its opposite end for the insertion of coins, a tray slidable in said casing and consisting of a resilient metal sheet 110 having a part thereof formed to provide a transversely extending tube at one end of the tray, means operatively mounted within said tube and coacting with the casing to releasably lock the tray against sliding movement 115 within said casing, said tray cooperating with the opposite side walls of the casing to provide coin receiving raceways, and the other end of said tray being provided with coin guard means positioned within the open end 120 of the tray. 125

130

of the casing and permitting of the insertion of coins into the raceways while preventing their extraction therefrom.

12. A coin bank comprising an elongated casing substantially closed at one of its ends and entirely open at its opposite end for the insertion of coins, a tray slideable in said casing and consisting of a resilient metal sheet having a part thereof formed to provide a transversely extending tube at one end of the tray, means operatively mounted within said tube and coacting with the casing to releasably lock the tray against sliding movement within said casing, said tray cooperating with the opposite side walls of the casing to provide coin receiving raceways, and the other end of said tray being provided with coin guard means positioned within the open end of the casing and permitting of the insertion of coins into the raceways while preventing their extraction therefrom, said tubular end of the tray being of substantially rectangular form in cross section and providing shoulders at opposite sides of the tray whereby upon the release of the locking means and the outward movement of the tray through the open end of the casing, the coins are stripped from the raceways.

13. A coin bank comprising a flat elongated casing, a tray longitudinally slideable within said casing and in conjunction with the opposite side walls thereof forming two coin receiving raceways, yieldable means on one end of said tray obstructing entrance to said raceways but permitting of the insertion of coins therein at one end of the casing while preventing the extraction of the coins, and releasable locking means carried by the other end of the tray cooperating with spaced means on one of the casing walls to lock the tray against sliding movement in the casing and to limit the withdrawal of the tray therefrom to prevent complete disconnection of the tray from the casing.

14. A coin bank comprising a flat elongated casing consisting of two similar sheet metal sections each bent to provide one complete compartment and one side wall of a second compartment and each of said sections having longitudinally extending flanges segregating said compartments from each other, and end flanges substantially completely closing said compartments at one of their ends, the other ends of the casing compartments being completely open, a tray having sections slideable in the respective compartments of the casing and provided with spaced slots receiving said longitudinal flanges of the casing, said tray sections dividing each compartment into a pair of coin receiving raceways, resilient guard means on one end of the tray partially closing the open ends of the casing compartments and permitting of the insertion of coins therethrough into the raceways while preventing the ex-

traction of the coins, and means for locking the tray within the casing against sliding movement relative thereto.

15. A coin bank comprising a casing having a plurality of compartments segregated from each other by longitudinally extending partitions, a tray slideable within the casing and consisting of a single resilient metal sheet folded intermediate of its length and having spaced longitudinal slots receiving the partitions of the casing and providing a series of tray sections slideable in the respective compartments of the casing, said metal sheet at one of its ends having resiliently yieldable guard means cooperating with the other end of the metal sheet to yieldingly retain the folded parts of the sheet in cooperative relation with the opposite side walls of the casing compartments to form a pair of coin receiving raceways in each compartment, and said guard means partially closing one end of the casing compartments but permitting of the insertion of coins therethrough into the raceways while preventing the extraction of the coins, and means for releasably locking the tray within the casing against sliding movement relative thereto.

16. A coin bank comprising a casing having a plurality of compartments segregated from each other by longitudinally extending partitions, a tray slideable within the casing and consisting of a single resilient metal sheet folded intermediate of its length and having spaced longitudinal slots receiving the partitions of the casing and providing a series of tray sections slideable in the respective compartments of the casing, said metal sheet at one of its ends having resiliently yieldable guard means cooperating with the other end of the metal sheet to yieldingly retain the folded parts of the sheet in cooperative relation with the opposite side walls of the casing compartments to form a pair of coin receiving raceways in each compartment, and said guard means partially closing one end of the casing compartments but permitting of the insertion of coins therethrough into the raceways while preventing the extraction of the coins, and means for releasably locking the tray within the casing against sliding movement relative thereto.

17. A coin bank comprising a casing having a plurality of compartments segregated from each other by longitudinally extending partitions, a tray slideable within the casing and consisting of a single resilient metal sheet folded intermediate of its length and having spaced longitudinal slots receiving the partitions of the casing and providing a series of tray sections slideable in the respective com-

parts of the casing, said metal sheet at one of its ends having resiliently yieldable guard means cooperating with the other end of the metal sheet to yieldingly retain the folded parts of the sheet in cooperative relation with the opposite side walls of the casing compartments to form a pair of coin receiving raceways in each compartment, and said guard means partially closing one end of the 10 casing compartments but permitting of the insertion of coins therethrough into the raceways while preventing the extraction of the coins, key operated locking means carried by the other end of at least one of the tray sections, one wall of said casing adjacent opposite ends thereof having means adapted to be engaged by said locking means to lock the tray within the casing against sliding movement, and to limit the withdrawal of the tray 20 from the casing, and each of the tray sections at the latter ends thereof being provided with means for stripping the coins from the raceways, as the tray is withdrawn.

In testimony that I claim the foregoing as 25 my invention, I have signed my name hereto.

CHARLES L'ENFANT.
